(57) **CLAIM**

The ornamental design for a display system for a gasoline pump, as shown and described.

DESCRIPTION

Our display system displays printed matter and is placed on top of a gasoline pump.

FIG. 1 is a top plan view of a display system for a gasoline pump showing our new design;

FIG. 2 is a front elevation view of the display system;

FIG. 3 is a rear elevation view of the display system;
FIG. 4 is a left side elevation view of the display system, the right side elevation being the mirror image; and,
FIG. 5 is a perspective view of the display system.

The broken line showing of printed matter which is placed behind the three transparent panels and a fragmented view of the top portion of a gasoline pump is for illustrative purposes only and forms no part of the claimed design.
